SANITARY PAD SUPPORT

Edward R. Sutter, Chicago, Ill., assignor to Beau-T-Form Foundations, Inc., a corporation of Illinois

Application July 30, 1949, Serial No. 107,805

7 Claims. (Cl. 128—291)

1

This invention relates to a sanitary pad support for a foundation garment and has a general object to provide a new and improved support of the character described.

A more particular object is to provide a support which may be permanently attached to a foundation garment without interfering with the normal use of the garment.

Another object is to provide a support having means for grasping a sanitary pad which may be placed in a position which holds the means out of contact with the body of the wearer when not in use.

Another object is to provide a support which may be attached to the inner surface of a foundation garment and having a laterally yieldable portion adapted to yield coincident with circumferential stretching of the foundation garment.

A further object is to provide a support of the character described having a supporting means enclosed within a flat cloth sheath to prevent chafing when worn by the user.

Other objects and advantages will become apparent from the following description taken in connection with the accompanying drawing in which:

Fig. 1 is a perspective view of the sanitary pad support of this invention and illustrated as mounted on the bottom part of a foundation garment shown in dotted lines.

Fig. 2 is an enlarged front view of the front support showing the internal structure thereof in dotted lines.

Fig. 3 is an enlarged front view of the rear support showing the internal structure thereof in dotted lines.

Fig. 4 is a cross-sectional view taken along line 4—4 of Fig. 3.

Fig. 5 is a plan view of a piece of cloth from which the sheath shown in Fig. 3 may be formed.

While the invention is susceptible of various modifications and alternate constructions, it is here shown and will hereinafter be described in a preferred embodiment. It is not intended, however, that the invention be limited thereby to the specific disclosure made but on the contrary it is intended to cover all modifications and alternative constructions falling within the spirit and scope of this invention as defined in the appended claims.

It is desirable that any sanitary pad support intended to be worn at the same time as a foundation garment be capable of lying flat

against the body of the wearer and provide a snug yet comfortable positioning of the pad. The pad is supported at the front and at the rear and each support should exert an upwardly directed pull on the pad.

As shown herein for purposes of disclosure, the sanitary pad supporting means comprises generally a front support 5 which is adapted to be attached as by sewing 6 to the inner surface of a foundation garment 10 herein illustrated fragmentarily and a rear support 7 which is adapted to be attached as by sewing 8 and 8a to the inner surface of the foundation garment at the rear thereof. Each support 5, 7 is positioned on the foundation garment so that the lower edge of the support is aligned with or slightly above the lower edge 11 of the foundation garment. Each support has a pad-grasping hook 9 associated therewith which is held above the lower edge 11 of the foundation garment when not in use and is adapted to depend below the lower edge 11 when necessary for the use of the wearer as hereinafter described.

The front support 5 as illustrated in detail in Fig. 2, comprises a cloth sheath 12 formed in the shape of a trapezoid. The sheath 12 may be formed of two separate pieces of cloth or of one cloth piece folded along the longer parallel side 13 and sewed or otherwise fastened together along the marginal edges leaving an opening 14 in the shorter parallel side 15 communicating with the interior of the sheath. The sheath is flat in order that it may lie smoothly and with the greatest amount of comfort against the body of the wearer when attached to a foundation garment.

A pad grasping hook 9 is loosely threaded on a flat strip 16 of elastic material and has an elongated narrow slot 17 adapted to receive and securely hold an end of a pad therein. The strip 16 of elastic material is folded at its approximately longitudinal center into the form of a V. The free ends 18 of the legs of the V are secured within the sheath to the upper edge thereof as by sewing 18 as viewed in Fig. 2. The strip 16 is of a length sufficient to have the base 19 of the V-shaped strip fall just below the shorter parallel side 15 of the sheath so as to project out of the opening 14 a short distance when the strip is secured within the sheath as above described. The hook 9 will normally seek a position on the strip 16 near the base of the V and will depend below the edge of the sheath when in usable position. The strip 16 being attached within the sheath at the free ends of the legs of the V is

free to stretch longitudinally to apply tension to the pad directing a yieldingly upward pull on the pad to hold it in proper position.

When the support is not in use, the hook **9** may be inserted into the sheath so that it will not dangle below the foundation garment. This is accomplished by pulling the hook away from the sheath so as to stretch the strip **16**, inverting the hook and inserting into the sheath with the narrow slot **11** of the hook entering the sheath first. The strip **16** will spring back to its normal unstrained position pulling the hook into the sheath and retaining the hook therein until the wearer wishes to pull it back out. As illustrated in Fig. 1, the hook is completely shielded within the sheath when so inverted and only a small portion of the strip **16** extends below the shorter parallel side **15** of the sheath.

The rear support **7** illustrated in detail in Figs. 3 and 4 has a flat cloth sheath **20** folded into the shape of a V having a right leg **21** and a left leg **22** converging into a common base **23**. The sheath **20** is preferably made of one piece of material (as illustrated in Fig. 5) but may be made from more than one piece. In the embodiment illustrated, a piece of cloth cut in the approximate N shape illustrated in Fig. 5 is folded along a line **24** between the adjacent surfaces of the legs of the sheath and the piece of cloth on either side of the fold line **24** is folded upon itself along a line **25** and **25'** respectively to form the enclosure of each leg of the sheath. The outer marginal edges of the legs and base are then bound together as by sewing **26** and the lower edge **27** of the base **23** is left open providing an entrance to the interior of the sheath. A foundation garment in performing its function of slenderizing the hips and thighs is capable of stretch circumferentially of the garment. The garment stretches in this manner when the wearer assumes a sitting position or bends forwardly from the hips. The sheath **20** is adapted to be attached to the inner surface of the foundation garment at the free ends of the legs **21**, **22** and when the garment is stretched circumferentially, the legs will move apart so as to not interfere with the normal function of the foundation garment.

A pad grasping hook **9** is loosely threaded on an elongated thin strip **28** of elastic material and has a narrow slot **29** to receive and securely hold one end of a pad. The strip **28** is folded intermediate its ends to form a V and the free ends of the strip are respectively attached within the sheath to the upper ends of legs of the sheath as by sewing **20**. The hook **9** depends below the sheath when in usable position and may be inverted and placed within the sheath when not in use in the manner described above in connection with the front support shown in Fig. 2. When the hook is placed within the sheath a portion of the strip **28** projects below the sheath, as illustrated in Fig. 1, to provide a convenient finger-hold with which to pull the hook out of the sheath.

The pad supports may be attached or removed from a foundation as desired or may be permanently sewn therein. The garment may be laundered without removing the pad supports as all parts of the supports are of washable fabrics except the hook **9**. When the wearer is moving about, the elastic strips stretch or contract as necessary to maintain a firm upwardly directed pull on the pad retaining it in proper position and the cloth sheaths protect the indi-

vidual's skin against chafing by the elastic strips.

It is believed apparent from the foregoing that I have perfected a vastly improved sanitary pad support for a foundation garment. With the use of my support, a sanitary pad may be worn when wearing a foundation garment without the necessity of a separate supporting structure about the hips.

I claim as my invention:

- 10 1. A sanitary pad support for a foundation garment comprising, in combination, a foundation garment, a front support including a trapezoidal shaped cloth sheath having an opening in its short parallel side communicating with the interior of the sheath, an elongated strip of elastic material folded intermediate its ends to form a V, said strip being attached at its free ends within the sheath to the longer parallel sides thereof, a pad-grasping hook loosely threaded on said strip and adapted to depend below said sheath in a first usable position and to be inverted and held within said sheath in a second position when not in use and means for attaching said sheath to the front inner surface of the foundation garment, and a rear support including a V-shaped cloth sheath having separate legs converging into a common base and an opening extending through the lower edge of the base communicating with the interior 15 of the sheath, an elongated strip of elastic material folded intermediate its ends and having its free ends respectively attached within the sheath to the free ends of the legs of said sheath, a pad-grasping hook loosely threaded on said 20 strip and adapted to depend below the sheath in a first usable position and to be inverted and held within said sheath in a second position when not in use and means for attaching said sheath to the inner rear surface of the foundation garment.

- 20 2. A supporting means for a wearable item comprising, in combination, an item-grasping hook loosely threaded on an elongated strip of elastic material, said strip being folded intermediate its ends into the shape of a V with the hook at the base of the V, a thin cloth sheath enclosing said strip and having the strip secured at its free ends to the upper edge of the sheath with the folded end of the strip substantially aligned with the bottom edge of the sheath, said sheath having only a single opening at its bottom edge, said hook depending below the sheath when in usable position and adapted to be inverted and held within the sheath by said strip 25 when not in use.

- 25 3. A supporting means for a wearable item adapted for use with a circumferentially stretchable garment comprising, in combination, a thin cloth sheath formed in a V-shape having separate legs converging into a common base and only a single opening in the bottom edge of said base communicating with the interior of the sheath, said sheath being adapted to be secured to a garment at the free ends of its legs to provide relative lateral movement of said legs coincident with circumferential stretching of the garment, an elongated strip of elastic material folded intermediate its ends to form a V, said strip being attached at its free ends within the sheath with the base of the V substantially aligned with the bottom edge of the sheath, and an item-grasping hook loosely threaded on said strip and adapted to depend below the sheath in a usable position and to be held within the sheath 30 when not in use.

4. A supporting means for a wearable item adapted for use with a circumferentially stretchable garment comprising, in combination, a thin cloth sheath formed in a V-shape with an opening in the bottom edge of the V communicating with the interior thereof, said sheath having a first strip of material forming one side of the base of the sheath and folded on a bias beyond the base to form a first leg and a second strip of material forming the other side of the base of the sheath and folded on a bias crossing the bias in said first strip to form a second leg of said sheath spaced and separate from said first leg, textile stitching binding the outer marginal edges of said strips together, said sheath being adapted to be secured to a garment at the free ends of its legs to provide relative lateral movement of said legs coincident with circumferential stretching of the garment, an elongated strip of elastic material folded intermediate its ends to form a V, said strip being attached at its free ends within the sheath with the base of the V substantially aligned with the bottom edge of the sheath, and an item-grasping hook loosely threaded on said strip and adapted to depend below the sheath in a usable position and to be held within the sheath when not in use.

5. A supporting means for a wearable item, comprising, in combination, a trapezoidal shaped thin cloth sheath opening only downwardly through the shorter parallel side thereof and adapted to be attached to a garment along the longer parallel side of the sheath, an elongated strip of elastic material folded intermediate its ends to form a V secured within the sheath at its free ends with the base of the V substantially aligned with the lower edge of the sheath, and an item-grasping hook loosely threaded on said strip adapted to depend below the lower edge of the sheath when in usable position and to be in-

verted and held within the sheath when not in use.

6. A supporting means for a wearable item comprising, in combination, an elongated strip of elastic material folded intermediate its ends, a thin cloth sheath enclosing said strip and securing the strip at its free ends within the sheath, said sheath having only a single opening along one edge thereof, and a pad-grasping hook loosely threaded on said strip and depending below the sheath in a usable position through said open edge when said strip is in normal position, said hook being adapted to be inverted and held within the sheath when not in use with the threaded end of the hook depending slightly below said open edge.

7. A cloth sheath for a supporting means for a wearable item adapted for use with a circumferentially stretchable garment comprising, a thin V-shaped cloth sheath having separate legs converging to a common base and an opening in the bottom edge of the base communicating with the interior of the sheath, said sheath being formed of one piece of material having two main portions and a first fold line positioned between said portions, each main portion being divided into two sub-portions positioned on either side of a second fold line and stitching securing the outer free marginal edges of the piece together when folded on said fold lines to form the cloth sheath.
